UNITED STATES PATENT OFFICE.

FREDERICK WILLIAM HOLLIK, OF GOUROCK, SCOTLAND, ASSINGNOR TO THE BAB-COCK & WILCOX COMPANY, OF BAYONNE, NEW JERSEY, A CORPORATION OF NEW JERSEY.

JIB CRANE.

Application filed September 7, 1922. Serial No. 586,603.

To all whom it may concern:

Be it known that I, FREDERICK WILLIAM HOLLIK, a subject of the King of Great Britain, residing at Gourock, in the county 5 of Renfrewshire, Scotland, have invented certain new and useful Improvements in Jib Cranes, of which the following is a specification.

My invention relates to improvements in 10 jib cranes which will be understood from the following description and the annexed drawings, in which Fig. 1 is an illustrative embodiment of one form of crane embodying my invention, and Fig. 2 is an enlargement 15 of a portion of Fig. 1.

In the crane illustrated, a frame 10 supports the structure, this frame being mounted movably in the usual way. Since the 20 particular mounting of the support for the crane is no part of my invention, detailed description thereof will be unnecessary to an understanding of my invention. On the frame 10 is a jib 11 pivoted at 12 in the usual manner.

25 The angular inclination of the jib 11 is controlled by a sector arm 13 pivoted at 14 on the framework of the crane, the sector 13 having one of its arms connected by a link 15 with the crane 11. The periphery of the 30 sector is provided with gear teeth 16 which are engaged by the teeth of a gear 17 connected by a bevel gear 18 driven by a bevel pinion 19 on the upper end of the shaft 20 supported in the crane frame. The lower 35 end of the shaft 20 is provided with gearing 21 by which the shaft may be driven through a motor 22. At the upper end of the jib is a jib lever arm 23 pivoted at 24 on the jib and carrying on its outer end suitable 40 pulleys, as 25 and 26, by which the cables or ropes 27 and 28 for lifting the load may be passed from the load to the winding mechanism on the crane frame.

45 As a means for counterbalancing the crane against the load, I provide a tank or receptacle which may be filled with any suitable liquid or granular material in order to provide the necessary counterbalance weight, and in order that this character of weight 50 may not spill, I support the receptacle 29, as at 30, on the ends of a pair of two-armed levers 31 which are pivoted at 32 on the crane frame 10. These arms are connected by the rod 33 with the sector 13 by a pivot 55 joint, as at 33^a, so that as the sector 13 is

turned to raise and lower the jib, and thereby decrease or increase the moment of the load, the arms 31 are correspondingly swung to shift the position of the weighted receptacle 29, and at the same time, by reason of 60 the pivotal connection of this receptacle with the arm 31, the receptacle itself will remain upright in all positions. By providing an arrangement, such as that described, the amount of weight necessary to counterbalance 65 the load can be readily changed by tilting the receptacle and pouring out some of the liquid or granular material if the counterbalance is heavier than the load required, and similarly additional material readily 70 available at the points of use of the crane weight.

As a back guy to control the action of the 75 jib arm 23 and also to assist in carrying the load directly to the crane frame, I provide a guy 34 which preferably will be of steel cable which is connected to the crane frame in a manner to be described more fully hereinafter and which passes over a 80 circular guide 35' formed as part of the lever 23, and preferably is attached near the outer end of the lever 23. The back guy 34, as shown best in Fig. 2, is connected to a yoke 35, the legs of which extend 85 through a plate or plates 36 held to the legs of the yoke and a spring 37 is interposed between the plate 36 and the member 38 of the crane frame. With the construction described, the sudden application of a 90 load to the end of the arm 23 will be transmitted through the back guy 34 and will be taken up through the spring 37, so as to absorb any shock to prevent the breaking 95 of the back guy 34. The back guy 34 passing over the guide 35' will permit the outer end of the arm 23 to lower as the jib is raised to a vertical position to swing the load inward so that the clearance height 100 of the upper end of the jib remains more nearly constant than would be the case if the arm 23 were rigidly connected to the jib 11. At the same time, the back guy 34 prevents the arm 23 from turning around the pivot 24 when the weight is applied to 105 the outer end of the arm.

In the illustrative form, the crane is provided with a single and also a multiple hoisting rope, the single rope 27 passing over the pulley 25 and a corresponding 110

pulley on the pivot 24 directly to the hoisting mechanism on the crane. The multiple hoisting rope 28 has one end attached to the lever 42 pivoted on the crane frame 5 in the manner to be described more fully hereinafter and from thence it passes over an idler on the pivot 24 and to and around a loose pulley 26 on the pivot 26'. It then passes successively around pulleys in the 10 hoisting block and on the pivot 26' as many times as desired and from the last pulley 393 on the pivot 26' over a loose pulley 394 to the hoisting drum 40, the standing or stationary portion of cable 28, as well 15 as the moving portion, being indicated at 39. In order that the standing and moving portions of this multiple cable shall not be shifted relatively when the load is to be shifted by the raising or lowering of 20 the jib, I pass the standing portion 39 of the rope around the pulley 391 which is concentric with the hoisting drum around which the moving portion of the cable extends and attach the end of this standing 25 portion 39 to a point 43 on a lever 42 which is pivoted at 44 on the crane frame. Since the standing and moving portions of the multiple hoisting rope extend between substantially the same points, it is obvious 30 that the raising and lowering of the jib will not affect the relative positions of these cables to cause a raising or lowering of the load by reason of this relative movement, which would be obtained if the standing 35 end 39 were connected directly to the frame of the crane so as not to be parallel at all times to the moving portions.

The outer end of the lever 42 is carried on a spring 45 having its lower end against 40 a seat 46 connected to the crane frame. An increase of load on the multiple cable hoist will be transmitted through the cables 28 and the standing end 39 to the lever 42 and will be resisted by the spring 45. 45 Nevertheless, the spring 45 will be compressed in accordance with the load on this portion of the hoist, so that the lever 42 will vary in its angular position around the center 44 in accordance with the load being lifted.

On the vertical shaft 20, which rotates the jib sector 13, I provide a screw thread and on this screw thread there is a nut 53 provided with suitable guides to prevent 55 its turning with the shaft 20, so that as the shaft 20 is rotated, the nut 53 will move up or down in accordance with the direction of rotation. The position of the nut 53 will therefore always have a predetermined 60 relation with the angular position of the jib 11.

In the illustrative embodiment, I mount on the arm 42 a switch box 55 having an arm 56 projecting into the path of an arm 54 65 on the nut 53. The winding drum for the

hoisting ropes is provided with a gear 41 driven by gears 47 and 48 from the motor pinion 49 on the motor 50. This motor may be provided with an electric brake 51 and the motor 22 with an electric brake 52. The 70 switch box 55 is connected by suitable wiring with the motors 51 and 52, so that when the arm 56 of the switch box is rotated by contacting with the arm 54 of the nut 53, the power to the motors 52 and 22 is shut off and the magnetic brakes applied.

It will be obvious by an inspection of Fig. 2 that the arms 56 and 54 will be moved toward each other either by an increase of the load on the hoist, which is transmitted through the standing end 39 to the lever 42 carrying the switch box 55, or by the rotation of the shaft 20 in a direction to lower the outer end of the jib 11. The parts are so arranged, however, that the arms 56 and 54 will not contact when light loads are carried by the jib even when the jib is dropped to its lowermost position, which would be when the arms 13 and 15 are in a straight line.

If, however, the load being lifted is excessive, then the lever 42, and the arm 56 with it, will be pulled down, so that as the crane 11 approaches its most nearly horizontal position, the arms 54 and 56 will contact to shut off the power and to apply the brakes. It will be seen that the arrangement provided is one which is calculated to prevent the crane overturning by providing a means for shutting off the power when the moment of the load exceeds a predetermined amount. Obviously this predetermined amount is a function of both the total load and the arm of that load which is its distance from the crane, and the device which I have provided operates when the moment of the load exceeds a predetermined amount, no matter whether that amount is made up of a very heavy load with a short arm or with a long arm and a lighter load.

It will be obvious that the embodiment of my invention may be varied within wide limits and it will be understood that the arrangement described is merely illustrative.

I claim:

1. In a jib crane, a load-lifting drum mounted on the crane frame, a pulley mounted coaxially with the drum, a load-lifting rope passing from the drum to the end of the jib and the weight to be lifted and returning over the end of the pulley to and partially around said pulley and anchored to the crane frame, and means to change the inclination of the jib.

2. In a jib crane, a hoisting drum and power-actuated means to move it, power-actuated means to change the inclination of the jib, a hoisting rope having its movable end passing around the drum, a lever having the standing end of the hoisting rope connected thereto, resilient means to resist the turning

of the lever by said rope, a control arm connected to and movable with said lever, and a contact piece connected to the jib and arranged to move therewith, said control arm 5 and said contact piece being arranged to be moved toward each other either by an increased pull on the standing end of the rope or by the motion of the jib toward the horizontal, said control arm being constructed 10 and arranged to suspend the motion of said power-actuated means when the control arm is contacted by the contact piece.

3. In a jib crane, means to hoist a load comprising a hoist rope passing over the 15 head of the jib and means to move the rope, a first movable member on the crane frame and connected to the standing end of the hoist rope, means to change the inclination of the jib, a second movable member arranged to 20 be moved in accordance with the angular motion of the jib, said movable members being constructed and arranged to be moved toward each other by the motion of the jib toward the horizontal and by the increase 25 in the weight on the hoisting rope, and means, actuated by the contact of said members, to suspend the operation of the hoisting means and the jib inclination changing means.

30 4. In a jib crane, means to change the inclination of the jib, means to hoist a load on said jib, automatic means to suspend the

operation of both of said means when the overturning moment of the load on the crane reaches a predetermined amount, said means 35 comprising a first member movable in accordance with the weight of the load being lifted, a second member movable in accordance with the annular motion of the jib, and a suspending mechanism adapted to be 40 rendered operative when said movable members occupy a predetermined relative position.

5. In a jib crane, means to change the inclination of the jib, means to hoist a load 45 on said jib, and automatic means jointly controlled by the operation of the means for changing the inclination of the jib and of the load hoisting means to suspend the operation of both of said means when the overturning moment of the load on the crane reaches a predetermined amount.

6. In a jib crane, an electric motor for changing the inclination of the jib, an electric motor for hoisting a load on said jib, 55 and means jointly controlled by the operation of the means for changing the inclination of the jib and of the load hoisting means for breaking the circuit to both of said motors, said jointly controlled means comprising a member which yields in accordance 60 with the load.

FREDERICK WILLIAM HOLICK.
